C. F. Brown

Steering.

No 8,142.

Patented Jun 10, 1851.

UNITED STATES PATENT OFFICE.

CHAS. F. BROWN, OF WARREN, RHODE ISLAND.

BALANCED RUDDER.

Specification of Letters Patent No. 8,142, dated June 10, 1851.

To all whom it may concern:

Be it known that I, CHARLES F. BROWN, of Warren, in the county of Bristol and State of Rhode Island, have invented a new and useful Improvement in the Rudder Employed in Steering Ships; and other vessels in water, and I do hereby declare that the following is a full, clear, and exact description of the same, reference being had 10 to the accompanying drawings, forming part of this specification, in which—

Figure 1, represents a side view of part of the stern of a vessel having the rudder attached. Fig. 2, is a full view of the same. Fig. 3, is a horizontal section of the same taken in the line α , α , shown in Fig. 1. Fig. 4, is also a horizontal section taken in the line $\ast$, $\ast$, shown in Fig. 1.

Similar letters of reference indicate corresponding parts in each of the several figures.

My invention consists in the employment of two rudders hung at a distance apart upon the same post, on each side; each of 25 the two being at the same distance from the post, and with the surfaces of the one parallel or nearly so to the surfaces of the other.

The effect intended to be produced by hanging the rudders at a distance from the 30 post on opposite sides, is to make the pressure caused by the resistance of the water (as the vessel passes through it) on each rudder balance that on the opposite one, and thus enable the steersman to keep the 35 helm in any position with facility. The position the rudders occupy, though it allows them to offer the same resistance to the vessel's progress, causes them to meet with but little resistance when moved in steering and 40 therefore reduces the amount of power necessary to be applied in steering the vessel.

To enable others skilled in the art to make and use my invention I will proceed to describe its construction and operation.

45 A, represents the vessel's stern post. B, the keel, E, is the rudder post, which I propose to make an iron shaft—other material may however be employed. C, C', are two rudders each consisting of a flat plate of 50 metal of a given form and size; or may be of wood; they are parallel with each other and are both united at the top and bottom by yokes D, in which half way between the two rudders, there are bosses fitting to the 55 post E, and firmly secured to it by keying

or otherwise. The rudder post is hung on the stern post in loops or eyes a , or in any convenient way.

The rudders may have motion communicated to them by any suitable steering apparatus such as is used with the common rudder. It will be understood by referring to Fig. 3, where the red circle denotes the path described by the edges of the rudders in turning, that as the rudders form chords to the said circle, they will offer but little resistance to the water when moving from one point to another, compared to that offered by the common rudder which is radial. In Fig. 4, the rudders are represented 60 amidships in black lines. In Figs. 1, 2, and 3, and also in red lines in Fig. 4, they are represented in the position they would occupy when the helm is hard a starboard, the inside face of C', and the outside face of C, 65 presenting inclined planes to the water and by their resistance altering the course of the vessel which will move in the direction of the red arrow Fig. 4. Both rudders being of the same size, at the same angle to the 70 line of the motion of the vessel, and at the same distance from a common axis the effect of the resistance will be the same on each, and will not tend to alter the position of the rudders; therefore no effort is required by the steersman to hold them, 75 whereas with the common rudder the steersman has to hold it against the water. When the helm is hard a port as shown in blue lines in Fig. 4 the outside face of C', and 80 the inside face of C, act upon the water, the vessel's motion being in the direction of the blue arrow.

I do not confine myself to any particular 85 form for the rudders C, and C', but what I claim as my invention and desire to secure 90 by Letters Patent, is—

The employment for the purpose of steering ships and other vessels in water, of two rudders hung upon and at equal distances 100 from the same center of motion and with their surfaces parallel or nearly so with each other in such a manner that the same resistance is offered to each by the vessel's motion through the water and both are balanced, substantially as herein described.

C. F. BROWN.
